DESIGN FOR A BUREAU

Michael Hallward, Swampscott, Mass.

Application September 22, 1945, Serial No. 122,253

Term of patent 14 years

(Cl. D33—6)

To all whom it may concern:

Be it known that I, Michael Hallward, a subject of the King of Great Britain, residing at Swampscott, in the county of Essex and Commonwealth of Massachusetts, have invented a new, original, and ornamental Design for a Bureau, of which the following is a specification, reference being had to the accompanying drawing, forming a part thereof.

In the drawing showing my new design, the single figure is a perspective view of the bureau. The other side is the same as illustrated, and the rear is plain and unornamented.

The dominant features of my design for the bureau shown in the drawing reside in the continuous molding extending around the top and sides of the bureau at the front and at the rear thereof and standing above the plane of the adjacent top and side surfaces of the bureau.

I claim:

The ornamental design for a bureau, substantially as shown and described.

MICHAEL HALLWARD.
